TREATMENT OF HYDROCARBONS

Filed June 22, 1943

UNITED STATES PATENT OFFICE

2,408,753

TREATMENT OF HYDROCARBONS

Robert E. Burk, Cleveland Heights, Ohio, assignor
or to The Standard Oil Company, Cleveland,
Ohio, a corporation of Ohio

Application June 22, 1943, Serial No. 491,755

8 Claims. (Cl. 260—671)

1

This invention relates to the treatment of hydrocarbon stocks to form alkyl aromatics such as ethyl benzene and iso-propyl benzene, and also branched chain aliphatics such as iso-hexanes, iso-heptanes, and iso-octanes, all of which are valuable for use as an aviation gasoline base stock, with lead tetraethyl, or blended with other stocks or in ratios other than those of normal recovery.

More particularly, the invention comprises a unitary process in which hydrocarbons are cracked so as to form an ethylene and propylene containing fraction, an aromatic containing fraction, and a butane and pentane containing fraction; and the first fraction combined with the latter two fractions through appropriate alkylation and isomerization and alkylation procedures, respectively.

It is an object of the invention to provide a unitary process for alkylating aromatics and (isomerized) aliphatics formed in the same cracking process, by means of olefins also formed in said cracking process, so as to utilize a substantial portion of the hydrocarbons formed in cracking to provide products of the greatest value for motor fuel purposes.

A further object of the invention is to provide a process in which essentially the same catalytic material may be used for the isomerization and both of the alkylations, and which material comprises essentially hydrogen fluoride and boron trifluoride.

Still a further object of the invention is the provision of a process in which the catalyst used in the isomerizing and alkylating is not deleteriously affected by the products of the cracking operation, and which catalyst can be recovered continuously and reused in the isomerization and either or both of the alkylations.

An additional object of the invention is the provision of a process in which the catalyst used in one alkylation may be transferred to and used in the other alkylation before separation of the catalyst from the off-gas.

Still a further object of the invention is to provide a process of great flexibility in which the olefins may be used selectively for alkylating either the aromatics or the iso-paraffins, i. e., the ethylene may be reacted with the aromatics and the propylene with the iso-paraffins, or the ethylene reacted with the iso-paraffins and the propylene with the aromatics, or in which both olefins may be reacted with both the aromatics and iso-paraffins.

A further object of the invention is the provi-

5 sion of a process in which a single catalyst recovery system may be used for the isomerization and both the alkylation processes to separate the catalyst from the off-gas and make it available for reuse.

Other objects of the invention will be apparent from the following description of an illustrative example which is to be read in connection with the sheet of drawings forming a part of the specification.

The cracking and separation of cracked products

In accordance with the invention, a cracking stock is subjected to "drastic" cracking, i. e., a high temperature for a relatively short time. The stock may vary from the lower gasoline range to the kerosene range, although different stocks will yield somewhat different products, and in different amounts when cracked, and the stock may be selected with this in view. The temperature may vary from about 1250° to 1750° F., depending on the stock, the cracking time, and the relative amounts of the products wanted. The time may vary from about 0.1 to 0.25 seconds depending on the stock, the temperature, and the relative amounts of the products wanted. The pressure may vary from about atmospheric to about 300 pounds per square inch depending on the other variables noted above.

30 The stock is fed through an inlet 1, to the cracking furnace 2, following which it is immediately quenched with water or oil in the conduit 3, and fed to the tower 5. If the quench is oil it is removed at 6 with any other condensate. 35 The vapor leaves the tower 5 through a conduit 1 and is subjected to a water quench as it moves to the tower 8. The water is removed for the most part at 9.

The hydrocarbons formed in the cracking operation are fractionated in the tower 8, the major portion of the gaseous products leaving the top at 10, where they are compressed by the pump 11 and sent to the tower 12, where the C₃ and lighter hydrocarbons are removed from the top 45 at 13 as a gas and sent to the supply line 14. The C₄ and heavier hydrocarbons are removed from the tower 8 through the conduit 15 and sent to the tower 18 by the conduit 17. Any C₄ and heavier hydrocarbons separated in the tower 12 50 may be added at 16 and sent to the tower 18.

The tower 18 serves to separate the C₅ and heavier hydrocarbons from the C₆ and lighter hydrocarbons. The C₅ and heavier hydrocarbons are removed at 19, and the C₆ and lighter hydrocarbons are sent to the tower 20 where any re-

2

maining C₃ and lighter hydrocarbons are separated as a gas and added to the supply 14. The C₄ and C₅ hydrocarbons may be separated in the tower 21, the C₅ hydrocarbons being sent to the supply line 22. The C₄ hydrocarbons are removed at 23 and if desired the butadiene may be separated at 24, the butadiene removed at 25 and the remaining C₄ hydrocarbons sent to the supply line 26.

If desired, the C₆ and higher hydrocarbons may be returned by adjusting the valves 27 and 28, and sent to a separate cracking furnace operated at about 20° to 50° F. higher than the temperature of the furnace 2 for further cracking. The products from this second cracking furnace may be fractionated in the manner described and the C₅, C₄ and lighter hydrocarbons added to the respective supply lines 22, 26 and 14. The C₆ and higher hydrocarbons are fed to the supply line 29.

In accordance with an illustrative example, the cracking stock may be a heavy naphtha, i. e., a major portion boiling within the range of 300 to 450° F. The cracking temperature may be 1380° to 1650° F., the time of cracking about 0.175 second and the pressure about 5 pounds per square inch. Such a cracking operation will produce products of about the following amounts:

Weight per cent on feed	
Ethylene	17 to 23
Propylene	27 to 33
Butadiene	4 to 9
Butylenes	3 to 7
Butanes	7 to 9
Pentanes	4 to 6
Benzene	7 to 13
Toluene	3 to 5
Xylenes	2 to 4

The ethylene and propylene are fed into the supply line 14, and to a suitable gas holder 14a, from which they may be withdrawn and used in the alkylation processes to be described. The C₄ and C₅ hydrocarbons are sent to their respective storage tanks 30 and 34. If desired the fractionator 21 may be omitted and the C₄ and C₅ hydrocarbons treated as a single fraction and sent to a common storage tank.

The C₆ and higher fraction contains a substantial amount of benzene (C₆), toluene (C₇) and xylenes (C₈). This fraction is fed from the supply line 29 to the fractionator 32. Provision is also made for augmenting the supply of benzene or other aromatics which may be admitted through the valve 33.

The fractionator 32 preferably separates the benzene and toluene; the former is sent through pipe 34 to a storage supply 35 and the latter through pipe 36 to storage supply 37. If desired, the benzene and toluene may be separated as a single fraction and sent to a common storage supply. The xylenes and heavier aromatics are removed from the bottom of the fractionator 32 and sent to a fractionator 38. If desired, the toluene may be separated with the xylenes and heavier aromatics. The fractionator 38 separates the wanted aromatics generally the C₈, C₉ and C₁₀ aromatics, such as xylenes, ethyl benzene, iso-propyl benzene, ethyl methyl benzene, diethyl benzene, methyl iso-propyl benzene, etc., and they are removed through the conduit 39 and sent to storage 40. The C₇ hydrocarbons may be included in the wanted products depending on the operation of the fractionators 32 and 38. The heavier alkylate is removed at 41 and may be

further cracked, dealkylated or otherwise used or disposed of.

The alkylation of aromatics

The benzene and/or toluene is then subjected to alkylation. Both may be alkylated together, particularly if they are separated as a single fraction, or each may be alkylated separately. Alternatively, only one may be alkylated; for example, the toluene may be withdrawn and used for making explosives and only the benzene alkylated. The alkylation is carried out in the presence of hydrogen fluoride as the essential catalyst promoted by a minor proportion of boron trifluoride.

For illustrative purposes, it may be assumed that the benzene is to be alkylated. Benzene is fed through conduit 42 to the aromatic alkylator 43. The valve 44 is opened and the valve 45 is closed. The mixture containing ethylene and propylene is admitted to the alkylator 43 through pipe 46. The catalyst is admitted through the conduit 47, valve 48 and conduit 49. Since the propylene is more reactive the conditions may be adjusted so that only the propylene will react and the product formed will be primarily isopropyl benzene (cumene). This is removed at 50 and returned at 51 for fractionation so that the alkylate ends as one of the wanted products in the storage 40. The amount of benzene in the alkylator 43 generally is in excess of the stoichiometric amount of propylene to be reacted, and the unreacted benzene may be recycled through the conduit 50, fractionated and returned to the alkylation zone through conduits 34 and 42. The unreacted ethylene and the catalyst are removed from the alkylator at 52. Valves 54, 57 and 58a are closed and valves 53, 56 and 58 are open so that ethylene and the catalyst pass to the conduit 59 to be used in the alkylation of isoparaffins to be described later.

The olefin containing gas and the benzene may be fed to the alkylator 43, concurrent, counter-current or both. Under the preferred conditions the aromatic will be in the liquid phase and the catalyst and olefin in the gaseous phase. However, all of the components may be in the vapor phase or in the liquid phase, depending primarily on the temperature and pressure of the operation. In a vapor phase operation, the temperature of the reaction, under the preferred conditions, is above the boiling point of hydrogen fluoride at the pressure used (67° F. at atmospheric pressure), for example, within the range of 80° to 210° F., preferably 90° to 150° F. In a liquid phase operation, the temperature would be -25 to 140° F.

The pressure may be varied over a wide range, but under the other conditions preferred a pressure of atmospheric to 250 pounds per sq. in. pressure is utilized. Under the preferred conditions the pressure should be low enough to permit the hydrogen fluoride catalyst to be gaseous except for such as may be dissolved in the benzene in the liquid phase at the temperature used.

The time in which the reaction occurs will depend upon the size of the reacting vessel, and the rate and nature of the flow of materials through it. Under the preferred conditions the time of reaction is very short and is of an order of from one-fifth minute to fifteen minutes, a time of from 20 to 300 seconds being entirely satisfactory.

The catalyst used in the process, as mentioned previously, is hydrogen fluoride promoted by a minor proportion of boron trifluoride. The

amount of boron trifluoride may vary from a trace up to 50 mol per cent. Large amounts of boron trifluoride are not required.

The amount of the catalyst employed is not critical except that a sufficient amount must be employed under the reacting conditions to permit the reaction to proceed to the extent of completion desired. Larger amounts permit shorter times of reaction and corresponding alterations in temperature and pressure and give better yields. Under the conditions of the process it is preferred to employ the minimum amount that will achieve the desired completeness of the reaction. In general the amount will vary from about 2 to 50%, an amount of the order of about 4 to 15% is preferred.

The mol ratio of olefin to benzene may be about 1 mol of olefin to 1 to 8 mols of benzene, but the higher ratios are preferred and the excess benzene is then recycled.

As a specific example, in which a propylene and ethylene containing gas is fed to the alkylator, and benzene is the aromatic to be alkylated, the reaction may be carried out at a temperature of 110° F. The contact time of the propylene and the benzene may be 35 seconds, the pressure may be 100 pounds per square inch. The amount of catalyst (hydrogen fluoride with a trace of boron trifluoride) may be about 14% based on the benzene in the reactor. The amounts of propylene and benzene may be 0.66 and 7.21 pounds per hour, respectively, the mol ratio of benzene to propylene being about 5.9 to 1.0. Under these conditions the iso-propyl benzene formed is about 1.03 pounds per hour.

While in the above examples benzene is described as the aromatic to be alkylated, toluene may be treated under the same conditions. If toluene is alkylated instead of benzene the product will be primarily methyl iso-propyl benzene; if both benzene and toluene are alkylated together, both iso-propyl benzene and methyl iso-propyl benzene will be formed as the primary products.

The isomerization of paraffins

The n-butane and n-pentane in the storages 31 and 30 are isomerized to form iso-butane and iso-pentanes. These may be isomerized together or separately. However, they can be isomerized separately with facility because of the simplicity of recycling the unisomerized fraction. For illustrative purposes, it may be assumed that the butane is to be isomerized separately. It is removed from the storage 31 and fed through a conduit 60 to an isomerizer 61. Catalyst from the conduit 47 may be admitted through the valve 62a and conduit 63. A pump 63a may be included in the conduit 63 to place the catalyst under pressure and liquefy the same. The liquefied catalyst is collected in the receiver 71. Above the liquid will be gaseous boron trifluoride under pressure. The liquid catalyst is admitted to the isomerizer 61 through valve 65. The isomerization is carried out preferably with the catalyst in the liquid phase, that is, with liquefied hydrogen fluoride containing boron trifluoride dissolved therein. This is accomplished by employing a temperature for the isomerization below the boiling point of the hydrogen fluoride at the pressure employed, or in other words, a pressure at least as great as the vapor pressure of the hydrogen fluoride at the temperature of the isomerization. Boron fluoride is dissolved in the liquefied hydrogen fluoride used as the catalyst and the amount dissolved depends

upon the partial pressure of the boron fluoride and the temperature. This may be increased, if desired, by the pump 64a in the conduit 64 and the boron trifluoride admitted through the valve 65a.

The isomerization is accomplished by thoroughly mixing the liquid catalyst and the butane for the required length of time, following which the mixture is transferred to a separator 62 in which the hydrocarbons separate as an upper layer and the catalyst separates as a lower layer. Generally, the stratification may be accomplished by settling, but centrifuging or other separating techniques may be employed.

The lower catalyst layer (which may be an emulsion of catalyst and hydrocarbon) is withdrawn in the conduit 63b and returned through the conduit 64b to the isomerizer 61 where it may be reused. In this way it will be apparent that large quantities of fresh catalyst are not required, but such as may be necessary can be admitted through the valves 65 and 65a. If the lower layer builds up with hydrocarbons, particularly unsaturates which may form a complex with the catalyst, a portion of the lower layer may be withdrawn, the catalyst removed therefrom by heating, and the catalyst returned to the conduit 47 on any of the zones in which it is used.

The upper layer containing substantial portions of iso-butane is withdrawn from the separator 62 through the conduit 66, and transferred to the fractionator 67 in which the iso-butane is removed at the top and transferred through the conduit 68 to the iso-paraffin alkylator 69. The n-butane not isomerized is withdrawn from the fractionator 67 by means of the conduit 70 and returned to the isomerizer 61 through the conduit 64b.

Provision is also made to admit an additional quantity of normal butane through the valve 72 if the amount obtained in the cracking process is not sufficient to utilize all of the olefin formed during cracking.

As has been mentioned previously, the isomerization preferably is carried out under sufficient pressure to maintain the butane and the catalyst in the liquid phase at the isomerizing temperature employed. This pressure is preferably accomplished by utilizing relatively high partial pressures of boron trifluoride and this partial pressure may be from 25 up to 550 pounds per square inch. Since the catalytic activity of the catalyst depends in part upon the amount of boron trifluoride, the activity may be controlled by regulating the partial pressure of the boron trifluoride. The amount of catalyst used may vary depending upon the speed of the reaction desired; in general, from 25 to 100 volume per cent of the catalyst based on the hydrocarbon is preferred. The temperature may vary from a relatively low figure, for example, -25° F. up to 215° F. Higher temperatures, however, not only require increased pressure to maintain the liquid phase but also tend to undesirable cracking. The length of time to which the hydrocarbon is subjected to the isomerizing catalyst may vary depending upon the extent of isomerization desired in a single pass. Inasmuch as provision is made for recycling, it may be more efficient to carry out the reaction for shorter periods accompanied by greater recycling; a period of from 15 minutes to 3 hours is preferred.

It should also be understood that the temperature, pressure, amount of catalyst, amount of boron trifluoride and the time of treatment are

more or less interrelated and that any one variable should be selected and adjusted with reference to the others for the most efficient operation. This consideration, however, goes only to efficiency and yields and not operability and, therefore, may be adjusted by those skilled in the art in view of the description herein.

As an illustrative example, n-butane may be subjected to the catalytic action of 50 volume per cent of liquid hydrogen fluoride in which is dissolved boron trifluoride in an amount as to provide a partial pressure of boron trifluoride of 300 pounds per square inch. Isomerization may be carried on for two hours at a temperature of 122° F. The product is found to contain about 27 per cent iso-butane.

The above process has been described particularly with reference to the isomerization of butane but it may be carried out in the same way with pentane. In this event pentane is withdrawn from storage 30 and treated in the same manner as previously described.

If the butane and pentane have not been separated by a fractionator such as shown at 21 so the normal hydrocarbon for isomerization is a mixture, or if it is desired to isomerize both the butane and pentane simultaneously by withdrawing from both the storages 30 and 31, this can also be accomplished in the same manner described previously. Under such circumstances, however, it is desirable to utilize an additional fractionator to separate the iso-butane and iso-pentane from the normal butane and normal pentane after isomerization so that both of the unisomerized, normal hydrocarbons may be returned through the conduit 70 for further isomerization.

Alkylation of iso-butane and/or iso-pentane

The iso-paraffins isomerized in the manner described previously are then alkylated with an olefin. In the following illustrative example it is assumed that the n-butane has been isomerized separately and that the iso-butane will be alkylated separately. The iso-butane coming from the fractionator 67 is introduced into the alkylator 69 through the conduit 63. Inasmuch as the alkylation preferably is carried out in the liquid phase, the catalyst may be introduced in the liquid phase from the receiver 71 through the valve 73. The olefin used for the alkylation in this example is the ethylene and catalyst containing gas left over from the alkylation of the aromatics, and which exists from the aromatic alkylator 43 through conduit 52 and valves 53, 56, 58 and conduit 59. A pump 75 may be provided to liquefy the hydrogen fluoride and place the boron fluoride under the proper pressure. Since in the illustrative example the propylene will have been used in alkylating the aromatics, the product formed in the alkylation of iso-butane with the remaining ethylene will be the isomeric hexanes.

The alkylation is accomplished by mixing the iso-butane with the catalyst in the liquid phase in the presence of the olefin; after the reaction has proceeded to the desired extent, the mixture is transferred to the separator 76 where the hydrocarbon and catalyst are separated preferably by gravity stratification. The separated catalyst layer (which may be a hydrocarbon-catalyst emulsion) may be returned through the conduit 77 to the alkylator 69 and reused. In this way relatively small amounts of fresh catalyst are required from the supply 71. If the catalyst layer

builds up too much in the form of a catalyst-hydrocarbon complex, a portion may be withdrawn and the catalyst removed therefrom by heating and the catalyst returned to the conduit 47 or any of the zones utilizing the catalyst.

The upper layer containing the alkylated products is withdrawn from the separator 76 through a conduit 78 and transferred to the fractionator 79. The alkylated products are separated at the bottom of the fractionator through a conduit 80 and sent to storage. Since the amount of iso-butane used preferably exceeds the amount stoichiometrically required for reaction with olefins, provision is made for recycling the excess iso-butane through the conduit 81 to the alkylator 69.

The butane fraction in the storage 31 also may contain butylenes, and if so, these may alkylate with the iso-butane in the isomerizer 61. Provision is made for withdrawing such alkylates at the bottom of the fractionator 67 through the conduit 82 and transferring them through the conduit 78 where they are separated with the wanted alkylated products in the conduit 80.

The alkylation reaction preferably should be carried out with an excess of the iso-paraffin to promote complete utilization of the olefin and repress polymerization thereof. In general, the mol ratio of olefin to iso-paraffin should be 1:2 to 12. The pressure should be sufficient to maintain the isobutane and the catalyst in the liquid phase. This may be accomplished preferably by employing a relatively high partial pressure of boron trifluoride. The temperature may vary from -30° up to 160° F. In general, the temperature and partial pressure of boron trifluoride in the alkylation zone are lower than in the isomerization zone. This suggests that the pump 74 may be omitted and the pressure in the supply 71 maintained at that desired in the alkylation. Any higher pressure for isomerization can be supplied by the pump 64a. The length of the reaction may vary from 15 minutes to 3 hours but the alkylation may be accomplished in some what shorter time than the isomerization. The amount of the catalyst may vary from 10 to 100 volume per cent depending upon the speed of the reaction desired, temperature, and pressure. It is preferred to carry out the alkylation with a large amount of hydrogen fluoride and a small amount of boron trifluoride or a large amount of boron fluoride and a small amount of hydrogen fluoride.

The amount of boron trifluoride dissolved in the liquid hydrogen fluoride depends on the pressure and temperature and may be expressed in terms of its partial pressure at a given temperature. The amount of the catalyst, the proportion of the two fluorides, the temperature and time of the reaction are more or less interrelated and should be adjusted with reference to each other. These adjustments are concerned more with efficiency and yields than with operability and may be adjusted by one skilled in the art for the most efficient operation in view of the disclosures herein.

As an illustrative example, iso-butane and ethylene in the proportion of about 1:0.7 mols may be reacted at 40° F. for 1 1/4 hours in the presence of liquid hydrogen fluoride in the amount of 50 vol. per cent of the iso-butane and an amount of boron trifluoride to provide a partial pressure of 150 pounds per square inch. Conversion to about 60% in the gasoline range is obtained. The gasoline contains about 25% iso-

pentanes, 36% iso-hexanes and 15% iso-heptanes, the remainder boiling below 350° F.

The above example has been described utilizing iso-butane. The process may be carried out under about the same conditions utilizing iso-pentane. For example, iso-pentane and ethylene may be introduced into the alkylator 69 in the ratio of about 1:0.4 mols at 40° F. for 1½ hours in the presence of 60 weight per cent hydrogen fluoride and an amount of boron trifluoride to provide a partial pressure of 50 pounds per square inch. The yield shows a conversion of about 76%. About 30% is iso-butane which is recycled for alkylation, about 20% iso-hexanes, about 17% iso-heptanes, about 10% iso-octanes and 19% higher products, most of which are within the gasoline range.

If desired a mixture of iso-butane and iso-pentane may be alkylated together under about the same conditions.

Recovery of the catalyst

The catalyst carried into the fractionator 79 with the hydrocarbon layer from the separator 76 is removed at the top of the fractionator 79 through the conduit 83 together with unreacted gases, such as C₁ to C₃ saturates and any small amount of unreacted olefins. In the illustrative example valves 54 and 57 are closed, valve 55 is open so that the catalyst is sent to an absorber 84 through the conduit 85. The absorber may be a packed column or bubble plate column. The absorbent is introduced as a liquid into the top of the absorber 84 by means of a conduit 85a. The catalyst is absorbed by or forms a loose chemical combination with the absorbent and is removed through the conduit 86. Any saturated C₁ to C₃ hydrocarbons in the supply line 14 which have been carried through the alkylators 43 and 69, after the catalyst has been extracted therefrom, exit as the off-gas in conduit 87 and may be used as fuel or for other purposes depending upon the composition therein.

The absorbent charged with the catalyst and removed through the conduit 86 is sent to a desorber 88 where the catalyst is removed, and sent through conduit 47 for use in the isomerizing or either of the alkylating reactions. The denuded absorbent is returned through the conduit 85a to the absorber 84.

The absorbent for separating the catalyst from the gas may be any of a large number of compounds which form a complex with or otherwise absorb hydrogen fluoride and boron trifluoride.

Examples are dihydroxyfluoboric acid; substituted and unsubstituted diaryl ketones, such as benzophenone, amines, basic nitrogen heterocyclic compounds, and other nitrogenous basic compounds such as diphenylamine, coal tar bases, and chlorinated amines; certain aromatic hydrocarbons, ethers such as anisole and diphenyl ether; and certain metal fluorides. The temperature under which the absorption operation is carried out will depend upon the absorbent used and the pressure conditions maintained and is such as to secure a desirable or maximum absorption. When benzophenone is the absorbent, a temperature from near the melting point of the benzophenone up to 300° F. may be used, preferably 160 to 210° F. The desorbing may be accomplished at a higher temperature at which the complex is destroyed at least to some extent to free the catalyst in the vapor form. In the case of benzophenone a temperature within the range of 300 to 530° F. may be used for desorption.

Any pressure may be used in the absorbing and desorbing operations.

Alternative procedures

5 In the examples described heretofore the propylene is used to alkylate the aromatics, and the ethylene is utilized to alkylate the iso-paraffins. If desired, this procedure may be reversed by closing valves 44, 53, 55, and 58 and opening valves 45, 54, 56, 57 and 58a.

10 In this operation the propylene and ethylene containing supply in the line 14 is sent through the open valve 45 to the alkylator 69. The propylene being the more reactive will be utilized to alkylate the iso-butane and/or iso-pentane. The catalyst and unreacted ethylene will exit through the conduit 83, open valves 57, 56 and 58a, through the conduit 89, so that the aromatic alkylation is accomplished with the ethylene and catalyst contained therein which is admitted through the conduit 89. In this procedure it may or may not be necessary to admit additional catalyst through the valve 48 depending on the amount desired with the aromatic alkylation. The products leave the aromatic alkylator through conduit 52 which will contain the saturated gases and the catalyst which will be sent through valve 54, conduit 85 and the catalyst will be absorbed and desorbed in the absorber 84 and desorber 88, respectively. In this operation the iso-paraffins alkylated with the propylene will have a slightly higher molecular weight. For example, if iso-butane is alkylated with propylene the product will consist primarily of isomeric heptanes, such as 2,2,3-trimethyl butane. The product formed in the alkylation of the aromatics will be primarily ethyl benzene.

Additional alternative procedures

40 If desired, both valves 44 and 45 may be opened and the mixture of ethylene and propylene fed to both of the alkylation zones. The alkylation in each zone may be sufficiently vigorous to react both the propylene and ethylene in each zone so that the products exiting through the conduits 52 and 83 contain nothing but the saturated gases and catalyst. In this event, valves 53 and 57 are closed, valves 54 and 55 are opened so that the catalyst from both alkylators is sent to the absorber 84.

45 It will be apparent in view of the above description that the process is extremely flexible in the mode of operation and the products to be obtained. In general, the manner in which the process is operated will depend upon the characteristics of the wanted products, the manner in which the alkylated aromatics and alkylated iso-paraffins are to be blended either together or separately for products of high anti-knock gasoline.

50 The process has the additional advantage in that a single catalyst may be used for both isomerization and alkylation reactions and may be continuously reused and recycled through the various zones depending on the relative requirements of each.

55 The process has the advantage of utilizing substantially all of the useful products of the cracking to form highly desirable final products. In general, the cracking may be conducted so that the proportion of the aromatics and aliphatics to be isomerized and/or alkylated may correspond stoichiometrically with the olefins formed by cracking and to be used in the alkylation processes.

It will be understood that the description of the invention is illustrative of a process and that the drawing is to facilitate an understanding of the process. It is not intended to show apparatus either in form or scale that is necessarily suitable for practicing the invention. Similarly no attempt is made to include all of the heaters, condensers, pumps and other apparatus that may be necessary, as all of these features will be apparent to one skilled in the art in view of the explanation of the process herein.

The invention is capable of many modifications in the details of operation, as will be apparent to one skilled in the art, and all such modifications are to be included as are within the scope of the following claims.

I claim:

1. The process which comprises heating hydrocarbons to a relatively high temperature for a short time to form ethylene and propylene, C₄ and C₅ aliphatic hydrocarbons, and aromatics, separating the C₃ and lighter hydrocarbons containing propylene and ethylene, an aliphatic fraction selected from the group consisting of C₄ hydrocarbons, C₅ hydrocarbons and a mixture thereof and comprising a normal paraffinic hydrocarbon, and a C₆ and heavier hydrocarbon fraction containing aromatics; introducing the propylene and ethylene containing fraction and the aromatics into an alkylation zone and reacting the propylene with at least a part of the aromatics, isomerizing at least part of the normal paraffinic hydrocarbon in the aliphatic fraction, transferring the ethylene from the first alkylation zone and alkylating the isomerized hydrocarbon with the ethylene.

2. A process in accordance with claim 1 in which the isomerization and both alkylations are carried out in the presence of a catalyst comprising hydrogen fluoride and boron trifluoride.

3. The process which comprises heating hydrocarbons to a relatively high temperature for a short time to form ethylene and propylene, C₄ and C₅ aliphatic hydrocarbons, and aromatics, separating the C₃ and lighter hydrocarbons containing propylene and ethylene, an aliphatic fraction selected from the group consisting of C₄ hydrocarbons, C₅ hydrocarbons and a mixture thereof and comprising a normal paraffinic hydrocarbon, and a C₆ and heavier hydrocarbon fraction containing aromatics, isomerizing at least part of the normal paraffinic hydrocarbon in the aliphatic fraction, introducing the propylene and ethylene containing fraction and the isomerized hydrocarbon into an alkylation zone, and alkylating the isomerized hydrocarbon with the propylene contained in the lighter fraction, transferring the unreacted ethylene and introducing it and at least part of the aromatics into a second alkylation zone and alkylating said aromatics with the ethylene.

4. A process in accordance with claim 3 in which the isomerization and both alkylations are carried out in the presence of a catalyst comprising hydrogen fluoride and boron trifluoride.

5. The process which comprises heating a hydrocarbon stock boiling in the gasoline-kerosene range to a temperature within the range of about 1250° to 1750° F., for a time within the range of about 0.1 to 0.25 second to crack said hydrocarbon stock and form ethylene and propylene, aliphatic hydrocarbons in the butane-pentane range, and aromatics, fractionating the products to yield a C₃ and lighter hydrocarbon fraction containing propylene and ethylene, an aliphatic

hydrocarbon fraction boiling in the butane-pentane range and comprising a normal paraffinic hydrocarbon, and a C₆ and heavier hydrocarbon fraction containing aromatics; introducing at least part of the aromatic containing fraction and the lighter propylene and ethylene containing fraction into an alkylating zone and reacting the propylene with at least a part of the aromatic in the presence of a catalyst comprising hydrogen fluoride and boron trifluoride at a temperature of 80 to 210° F., and at a pressure of up to 250 pounds per square inch but not more than that necessary to maintain the catalyst in the vapor phase, withdrawing the unreacted ethylene in admixture with catalyst, isomerizing the normal paraffinic hydrocarbon in the aliphatic containing fraction at a temperature of -30° F. to 215° F. in the presence of a catalyst comprising liquid hydrogen fluoride in which is dissolved boron trifluoride under a partial pressure of 50 to 550 pounds per square inch, separating the isomer and transferring it to a second alkylation zone, introducing the unreacted ethylene and catalyst withdrawn from the first alkylation zone into the second alkylation zone, alkylating the isomer at a temperature of -30 to 160° F. in the presence of liquid hydrogen fluoride containing dissolved boron fluoride under a partial pressure of 50 to 200 pounds per square inch, transferring the unreacted products of the lighter fraction and catalyst contained in the same to a recovery zone, separating the catalyst from the unreacted lighter products, and returning the catalyst for reuse.

6. The process which comprises heating a heavy naphtha hydrocarbon stock to a temperature within the range of about 1380 to 1650° F., for about 0.175 second to crack said hydrocarbon stock and form ethylene and propylene, aliphatic hydrocarbons in the butane-pentane range, and aromatics, fractionating the products to yield a C₃ and lighter hydrocarbon fraction containing propylene and ethylene, an aliphatic hydrocarbon fraction boiling in the butane-pentane range and comprising a normal paraffinic hydrocarbon, and a C₆ and heavier hydrocarbon fraction containing aromatics; introducing at least part of the aromatic containing fraction and the lighter propylene and ethylene containing fraction into an alkylation zone and reacting the propylene with at least a part of the aromatic in the presence of a catalyst comprising hydrogen fluoride and boron trifluoride at a temperature of 90° to 150° F., and at a pressure of about 80 to 150 pounds per square inch, withdrawing the unreacted ethylene in admixture with catalyst, isomerizing the normal paraffinic hydrocarbon in the aliphatic containing fraction at a temperature of 65° to 160° F. in the presence of a catalyst comprising 25 to 100 volume per cent liquid hydrogen fluoride (based on the hydrocarbon) in which is dissolved boron trifluoride under a partial pressure of 150 to 350 pounds per square inch, separating the isomer and transferring it to a second alkylation zone, introducing the unreacted ethylene and catalyst withdrawn from the first alkylation zone into the second alkylation zone, the isomer being stoichiometrically in excess of the ethylene, alkylating the isomer at a temperature of 10° to 105° F. in the presence of liquid hydrogen fluoride containing dissolved boron fluoride under a partial pressure of 50 to 200 pounds per square inch, recycling the unreacted isomer, withdrawing the alkylated products, transferring the unreacted

products of the lighter fraction and catalyst contained in the same and contacting them with an absorbent, desorbing the catalyst from the absorbent, and returning the catalyst for reuse.

7. The process which comprises heating a hydrocarbon stock boiling in the gasoline-kerosene range to a temperature within the range of about 1250° to 1750° F., for a time within the range of about 0.1 to 0.25 second to crack said hydrocarbon stock and form ethylene and propylene, aliphatic hydrocarbons in the butane-pentane range, and aromatics, fractionating the products to yield a C₃ and lighter hydrocarbon fraction containing propylene and ethylene, an aliphatic hydrocarbon fraction boiling in the butane-pentane range and comprising a normal paraffinic hydrocarbon, and a C₆ and heavier hydrocarbon fraction containing aromatics; isomerizing the normal paraffinic hydrocarbon in the aliphatic containing fraction at a temperature of -30° F. to 215° F. in the presence of a catalyst comprising liquid hydrogen fluoride in which is dissolved boron trifluoride and under a partial pressure of 50 to 550 pounds per square inch, separating the isomer and transferring it to an alkylation zone, transferring the lighter ethylene and propylene containing fraction to the alkylation zone and reacting the propylene and at least part of the isomer at a temperature of -30 to 160° F. in the presence of liquid hydrogen fluoride containing dissolved boron fluoride under a partial pressure of boron trifluoride of 50 to 200 pounds per square inch, withdrawing the unreacted ethylene in admixture with any catalyst, introducing at least part of the aromatic containing fraction and the withdrawn ethylene and catalyst into a second alkylating zone, and reacting the ethylene with at least a part of the aromatic in the presence of a catalyst comprising hydrogen fluoride and boron trifluoride at a temperature of 80 to 210° F., and at a pressure up to 250 pounds per square inch, but not more than that which will maintain the catalyst in the vapor phase, withdrawing the unreacted products of the lighter fraction and catalyst from the second alkylating zone, separating the catalyst from the unreacted lighter products, and returning the catalyst for reuse.

8. The process which comprises heating a heavy naphtha hydrocarbon stock to a temperature within the range of about 1380 to 1650° F., for a time within the range of about 0.1 to 0.25 second to crack said hydrocarbon stock and form ethylene and propylene, aliphatic hydrocarbons in the butane-pentane range, and aromatics, fractionating the products to yield a C₃ and lighter hydrocarbon fraction containing propylene and ethylene, an aliphatic hydrocarbon fraction boiling in the butane-pentane range and comprising a normal paraffinic hydrocarbon, and a C₆ and heavier hydrocarbon fraction containing aromatics; isomerizing the normal paraffinic hydrocarbon in the aliphatic containing fraction at a temperature of -5° F. to 160° F. in the presence of a catalyst comprising 25 to 100 volume per cent liquid hydrogen fluoride (based on the hydrocarbon) in which is dissolved boron trifluoride under a partial pressure of 150 to 350 pounds per square inch, separating the isomer and transferring it to an alkylation zone, transferring the lighter ethylene and propylene containing fraction to the alkylation zone and reacting the propylene and at least part of the isomer at a temperature of +10° to 110° F., in the presence of liquid hydrogen fluoride containing dissolved boron fluoride under a partial pressure of boron trifluoride of 50 to 200 pounds per square inch, recycling the unreacted isomer, withdrawing the alkylated products, withdrawing the unreacted ethylene in admixture with any catalyst, introducing at least part of the aromatic containing fraction and the withdrawn ethylene and catalyst into a second alkylating zone, and reacting the ethylene with at least a part of the aromatic in the presence of a catalyst comprising hydrogen fluoride and boron trifluoride at a temperature of 90° to 150° F., and at a pressure of 80 to 150 pounds per square inch, withdrawing the unreacted products of the lighter fraction and catalyst from the second alkylation zone and contacting them with an absorbent, desorbing the catalyst from the absorbent, and returning the catalyst for reuse.
